CASING FOR AUTOGRAPHIC REGISTERS

Joseph R. Hermann, Kenmore, N. Y., assignor to Moore
Business Forms, Inc., Niagara Falls, N. Y., a corporation of Delaware

Application December 9, 1954, Serial No. 33,459

Term of patent 14 years

(Cl. D64—11)

FIG. 2.

FIG. 3.

Fig. 1 is a perspective view of a casing for an auto-graphic register showing my new design;

Fig. 2 is a front elevational view of the casing;

Fig. 3 is a top plan view of the same.

I claim:

The ornamental design for a casing for autographic registers, as shown.
